UNITED STATES PATENT OFFICE.

CHARLES EDGAR SMITH, OF REDONDO BEACH, CALIFORNIA.

CONVERTIBLE BATH-SPRAY.

1,171,149.

Specification of Letters Patent.

Patented Feb. 8, 1916.

Application filed August 5, 1915. Serial No. 44,846.

To all whom it may concern:

Be it known that I, CHARLES EDGAR SMITH, a citizen of the United States, residing at Redondo Beach, in the county of Los Angeles and State of California, have invented a new and useful Improvement in Convertible Bath-Sprays, of which the following is a specification.

My invention relates to bath sprays and the like and has for an object the provision of a device capable of being used as a spray or in connection with a syringe for rectal or vaginal purposes.

A further object is to provide a simplified structure which may be readily attached to the usual faucet of bath tubs in such a manner that the spray will be directed longitudinally of the tub and confined within the tub.

20 A further object is to provide means whereby the device may be easily disassembled for the purpose of cleaning, etc.

A further object is to provide means whereby the water may be selectively discharged from the device in the form of a spray from the sides or in a jet from the bottom, the opening of one of the water outlets serving to simultaneously close the other.

30 Other objects may appear in the description.

I am aware that a patent to one T. G. Fischel was issued Dec. 3, 1912, Serial No. 1,046,285, for a device embracing a bath spray attachable to a bath tub faucet, but I am not aware that any patent has ever been issued for a combination bath spray and syringe, as herein set forth.

Referring to the drawings, in which similar characters of reference indicate the same parts throughout the several views, Figure 1 is an elevation of my combination spray and syringe attached to the usual bath tub faucet; Fig. 2 is a bottom view; Fig. 3 is an elevation at right angles to Fig. 1; Fig. 4 is a sectional elevation of Fig. 3; Fig. 5 is a horizontal section of Fig. 4 on the line 5—5; and Fig. 6 is a section of the same on the line 6—6.

50 My device is attachable to the usual combination hot and cold water faucet 1 of a bath tub and the pressure and temperature of the water is regulated by means of the handles 2 and 3, in the usual manner. I provide a cylindrical body which is tapered from the upper end to the lower end with an

enlarged end 4 at the top and a reduced end 5 at the bottom. An annular recess 6 within the upper end 4 receives the flange 7 of a rubber gasket 8 which is tightly held in the recess by means of a retaining ring 9 threaded on the outer periphery of the end 4 and is suitably knurled so as to provide an easy means of turning the ring. A set screw 10 serves to hold the ring permanently in position on the body and prevents the ring from turning when the body is turned for opening and closing the outlets, as hereinafter described. The gasket 8 has a central opening 11 which is flared outwardly at the top and adapted to fit over the lower end of the faucet 1, and an opening 12 in the ring 9 is provided which registers with the opening in the gasket and through which the faucet is inserted when the device is applied for use.

The lower reduced end 5 of the body has a central bore or chamber 13 and a threaded stem 14 extending downwardly from the bottom thereof. An outer sleeve 15 which is tapered downwardly to conform to the body has a knurled flange 16 opposite the bottom of the body by means of which the sleeve may be turned on the body, and a reduced extension 17 which is pivotal on the reduced end 5 of the body. The extension 17 of the sleeve is bored to snugly fit the outer periphery of the end 5 of the body and the lower end of the end 5 and the bore of the extension 17 are formed on a taper so as to form a valve seat. A cap nut 18 is threaded on the stem 14 of the end 5 of the body and a suitable gasket 19 of rubber or leather is interposed between the nut and the end of the extension for holding the sleeve on the body and for preventing a leakage of the water therefrom.

A horizontal extension 20 is formed on or secured to the extension 17 of the sleeve which has a horizontal bore 21 extending the full length thereof and which is adapted to register with a bore 22 in the wall of the reduced end 5 of the body when the device is used as a syringe. The outer end of the horizontal extension 20 has annular ribs 23 formed thereon for holding the end of a rubber or flexible tube 24 securely in position thereon, the other end of the tube being attached to a syringe.

The periphery of the inner cylinder of the body has a plurality of relatively small perforations 25 which are arranged in rows ver-

tically thereon, and the outer sleeve 15 is provided with an elongated opening 26 which is sufficiently large as to expose all of the perforations 25 in the body when the device is used as a spray. The perforations 25 in the main portion of the body and the single bore 22 in the reduced end 5 thereof are arranged in radial lines on the quarters of the circle as shown, or at any other convenient angle so that the turning of the outer sleeve 15 on the body will cause the small spray perforations 25 to register with the large opening 26 in the outer sleeve and simultaneously move the small bore 22 in the end 5 from registration with the bore 21 of the extension 20, or vice versa.

Pins 27 are secured in the lower wall 28 of the upper end 4 of the body and similar pins 29 are secured in the upper end of the sleeve 15 at points on the peripheries of the two members which will correspond to the maximum movement of the sleeve on the body so as to limit the movement of the sleeve, or lugs may be used for this purpose instead of the pins if desired. A set screw 30 may be secured in the nut 18 for holding the nut firmly and immovably on the stem 14 when the sleeve is turned.

The body and the sleeve 15 are tapered so as to form a perfectly water tight connection and they should be ground together for obtaining the best results. The gasket 8 should be of a very good quality of rubber so that when forced on the lower end of the faucet the lower end of the gasket may be expanded within the cylinder and held on the faucet sufficiently tight as to form a water tight connection. The bore 21 should be substantially of an equal area to that of the faucet so that the pressure of the water will not force the device off of the faucet.

When used as a spray, the sleeve 15 may be adjusted on the body before attaching the device to the faucet by grasping the knurled ring 9 in one hand and the knurled flange 16 of the sleeve in the other hand and turning the sleeve on the body until the perforations 25 register with and are entirely exposed by the large opening 26 of the sleeve. This movement of the sleeve causes the movement of the bore 22 in the end 5 of the body to move out of registration with the bore 21 in the extension 20, and the water being turned on at the faucet, after having first forced the device firmly into position on the faucet, the water will then be sprayed from the perforations into the tub.

When used in connection with a syringe for vaginal or rectal treatments, the sleeve is turned on the body in a direction the reverse of that just described, the opening 26 moving out of registration with the perforations 25 and these perforations being covered by the wall of the sleeve, while the bores 21 and 22 at the lower end of the device are

moved into registration and the water is discharged from the extension 20 in a jet through the tube 24. The pressure in the tube may be regulated at the faucet and the temperature of the water may also be regulated to suit conditions.

The pins 27 and 29 on the body and the sleeve limit the movement of the sleeve on the body so that an extreme movement of the sleeve until the pins are in engagement will completely open one and close the other of the outlets.

It is obvious from the foregoing description that my improved device may be readily disassembled for any purpose by the removal of the retaining ring 9 and the cap nut at the bottom, and any wear between the two main elements may be compensated for by the tightening of the nut on the lower stem of the end 5 and the re-adjustment of the set screws.

Having thus described my invention, what I claim is:—

1. In a device of the character described, the combination with the water faucet, of a cylinder detachably and frictionally held on the faucet provided with means for spraying the water from the sides thereof and an outlet disposed at right angles to the cylinder through which the water may be discharged in a jet, and means for converting the discharge of the water from the cylinder in the form of a spray and jet, at will.

2. In a device of the character described, the combination with the water faucet, of a cylinder detachably and frictionally held thereon and provided with spraying outlets on the side thereof and a single and substantially larger outlet communicating with and extending outwardly from the cylinder at right angles for discharging the water from the cylinder in the form of a jet, and common means for selectively regulating the discharge of the water from either of said outlets in the form of a spray and a jet.

3. In a device of the character described, the combination of the water cylinder provided with a removable cap and friction element seated therein and peripheral water spraying means, a removably held water outlet extending at right angles from the cylinder having a bore communicating with said cylinder, and means for converting the discharge of water from said cylinder from a spray to a jet, and vice versa, at will.

4. In a device of the character described, the combination of the vertically disposed water cylinder provided with a plurality of peripheral apertures, a detachably held cap on the top of the cylinder, a friction element seated in said cap, a neck extending from said cylinder provided with a horizontally disposed outlet communicating with said cylinder, and means removably held on said neck and adapted to register at will with

said horizontal outlet for discharging the water therefrom in a jet, the cylinder being arranged to prevent the discharge of the water from said cylinder simultaneously 5 from said peripheral apertures and said horizontal outlet.

5. In a device of the character described, the combination of the vertically held water cylinder provided with a group of peripheral 10 outlets and water receiving means at the top thereof, a contracted neck below the receiving end of the cylinder having an outlet passage in communication with said cylinder, and a detachably held horizontally disposed member on said neck having a passage 15 adapted to register with the outlet in

said neck for permitting the discharge of the water from said cylinder therethrough and for converting the discharge of the water to the form of a jet and capable of 20 movement on said neck for closing the outlet in the neck and converting the discharge of the water from the cylinder to the form of a spray, at will.

Signed at Los Angeles, in the county of 25 Los Angeles, and State of California, this 30th day of June, 1915.

C. EDGAR SMITH.
